UNITED STATES PATENT OFFICE.

RUSSELL J. GRAY, OF MINNEAPOLIS, MINNESOTA, ASSIGNOR TO GRAY COMPANY, INC., OF MINNEAPOLIS, MINNESOTA.

PNEUMATIC GREASE GUN.

Application filed January 14, 1927. Serial No. 161,128.

My invention relates to pneumatic grease guns. An object is to provide a device of this character by means of which grease for lubricating purposes may be effectively delivered. While intended more particularly for use in lubricating parts of motor vehicles, it will be obvious that there are other places where my device may be used to advantage for obtaining efficient and timely lubrication of moving parts.

The full objects and advantages of my invention will appear in connection with the detailed description thereof, and the novel features of my inventive idea will be particularly pointed out in the claims.

In the accompanying drawings which illustrate a practical embodiment of my invention,

Fig. 1 is a side elevational view of the device. Fig. 2 is a top plan view. Fig. 3 is a view in vertical longitudinal section. Fig. 4 is a view in vertical section through a control valve showing it in open position. Fig. 5 is a similar view but showing the valve in closed position. Fig. 6 is a view in section on the line 6—6 of Fig. 5. Fig. 7 is a view in section on the line 7—7 of Fig. 3.

Referring to the construction shown in the drawings, the numeral 10 designates a grease receptacle which is provided with a detachable cover 12 having a handle 14. The receptacle 10 is secured upon a shelf 16 formed by the upper end of an inverted cup-shaped member 18. For convenient use of the device, the receptacle is mounted on wheels and for this purpose an axle 20 is bolted to the lower margin of the member 18 and the ends of the axle are provided with wheels 22 and 24. Furthermore, to the member 18 is secured a forwardly extending frame 26 in which is swivelly mounted a fork 28 on the lower end of which a wheel 30 is rotatably mounted. A handle 32 is pivotally attached to the front end of the frame for moving the device into the desired position. A tool box 34 is mounted on the frame. A tubular member 36 is positioned in the receptacle 10 with its lower end extending through the shelf 16 and provided with a nut 38 for holding the tubular member in place. The bore of the tubular member at its upper end is enlarged to receive an upwardly opening check valve 40 normally held on its seat by a spring 42 interposed between the valve and a screw plug

44 which closes the upper end of the bore. A pipe section 46 is screwed into the wall of the tubular member 36 adjacent the valve 40. The outer end of the pipe section 46 is screwed into a pipe section 48, a packing gland 50 being provided for the engaged ends of the two pipe sections. The pipe section 48 extends through the wall of the receptacle 10 and its outer end is connected by a screw threaded coupling 52 with a socket member 54 which receives the ball-like end 56 of a pipe section 58 to the outer end of which is attached a flexible tube 60 for delivering the grease to the desired place. The socket member 54 contains a spring 62 which holds the ball member 56 firmly but adjustably in contact with the reduced outer end of the socket member. The wall of the hollow member 36 is provided with a perforation 64 located just above the bottom 70 of the receptacle 10. A cylinder 66 is held between the shelf 16 and a head 68 secured in place by rods 70 shown in Fig. 7. A piston 72 works in the cylinder 66 and this piston carries an upwardly extending rod 74 constituting a plunger which works in the bore of the hollow member 36. The piston 72 and attached plunger 74 are normally held in lowered position by a coiled spring 76. The wall of the cylinder near its upper end is provided with a perforation 78 for escape of air when the piston is raised in the manner now to be described. The head 68 is provided with a perforation to which is fitted an elbow 80 having a flexible tube 82 attached thereto. The other end of the flexible tube 82 is attached to a valve casing 84 to which is also attached a flexible tube 86 leading from any convenient source of compressed air. A stem 88 is slidably mounted in the valve casing 84 and extends through the upper wall thereof, the valve chamber being closed at the bottom by a screw plug 90. Secured to the lower end of the stem 88 is a valve 92 adapted to cooperate with a valve seat 94 so that when the valve is closed as shown in Fig. 4, compressed air is prevented from passing from the tube 86 into the tube 82. When the valve is in open position as shown in Fig. 5, compressed air passes from the tube 86 through longitudinal slots 96 in the valve stem 88 and goes into the tube 82. Secured to the upper end of the stem 88 is a valve 98 outside of the casing and adapted to cooperate with a seat 110

100 formed in the casing. The valve 98 terminates in a button 102 by means of which the stem may be slid up and down. When the stem is in the position shown in Fig. 4, 5 compressed air in the tube 82 is permitted to escape past the valve 98. The sides of the receptacle 10 are provided with hooks 104 upon which the flexible tubes may be hung when not in use.

10 The operation and advantages of my invention will be readily understood in connection with the foregoing description. When the device is to be used, the delivery tube 60 is attached to the place which is to be lubricated. The valve stem is then moved from the position shown in Fig. 4 into that shown in Fig. 5 so that compressed air passes through the tube 82 and lifts the piston 72 and attached plunger 74. The latter forces the grease which is in the tubular member 36 past the check valve 40 and through the delivery tube 60. When the stem is moved back into the position shown in Fig. 4, the supply of compressed air which 20 was delivered into the tube 82 is shut off and the pressure therein is relieved through the slots in the stem past the valve 98. The spring 76 now forces the piston and attached plunger downwardly, the check valve 40 closing at this time so that a vacuum is produced in the bore of the member 36. As soon as the plunger 74 has moved below the perforation 64, grease is drawn into the bore in the hollow member by the vacuum therein 30 so that the device is ready for delivering another charge of grease.

I claim:

1. A pneumatic grease gun comprising a hollow supporting member, a main grease 40 receptacle mounted on the upper end of said

hollow member, a detachable cover for the upper end of said receptacle, a tubular member extending up from the bottom of said receptacle, a cylinder in said hollow member extending down from the bottom of said receptacle, a piston working in said cylinder, an upwardly extending rodlike plunger secured to said piston and working in said tubular member, a delivery tube extending from the upper end of said tubular member, 50 said tubular member having a perforation in its wall adjacent the bottom of said receptacle, a spring in said cylinder normally holding said piston and plunger in lowered position, and a tube for supplying compressed air to the lower end of said cylinder. 55

2. A pneumatic grease gun comprising a hollow supporting member, a main grease receptacle mounted on the upper end of said hollow member, a detachable cover for the upper end of said receptacle, a tubular member extending up from the bottom of said receptacle, a cylinder in said hollow member extending down from the bottom of said receptacle, a piston working in said cylinder, 60 an upwardly extending rodlike plunger secured to said piston and working in said tubular member, a delivery tube extending from the upper end of said tubular member out through the side wall of said main receptacle, said tubular member having a perforation in its wall adjacent the bottom of said receptacle, a spring in said cylinder normally holding said piston and plunger in lowered position, and a tube for supplying 70 compressed air to the lower end of said cylinder. 75

In testimony whereof I hereunto affix my signature.

RUSSELL J. GRAY.
